FAN

Peter P. Grad, Woodstock, N.Y., assignor to Rotron
Manufacturing Company, Inc., Woodstock, N.Y.,
a corporation of New York

Filed Nov. 25, 1966, Ser. No. 4,811

Term of patent 14 years

(Cl. D62—4)

FIG. 1

FIG. 2

FIGURE 1 is an elevation view of the fan showing one side of my new design; and

FIGURE 2 is a perspective view of the fan showing the other side, the top and one edge thereof; the bottom and other edge being mirror images of the top and said one edge, respectively.

I claim:

The ornamental design for a fan, substantially as shown and described.
